UNITED STATES PATENT OFFICE.

CASPER L. REDFIELD, OF CHICAGO, ILLINOIS.

PNEUMATIC PUMP.

1,205,391.

Specification of Letters Patent.

Patented Nov. 21, 1916.

Application filed March 31, 1913. Serial No. 757,861.

To all whom it may concern:

Be it known that I, CASPER L. REDFIELD, a citizen of the United States of America, and a resident of Chicago, county of Cook, and 5 State of Illinois, have invented certain new and useful Improvements in Pneumatic Pumps, of which the following is a specification.

My invention relates to pneumatic pumps 10 of the submerged type, and has for its object improvements in pumps of that character.

In the accompanying drawings Figure 1 is 15 an elevation, partly in section; Fig. 2 is an enlarged plan; Fig. 3 is a section on line 3—3 of Fig. 2, showing the upper portions only; Fig. 4 is a section on line 4—4 of Fig. 3; Fig. 5 is a section on line 5—5 of Fig. 2, showing the lower portions only; and Fig. 6 20 is a perspective view of the main valve.

The pump in the present case consists of 25 two adjacent cylinders 10 having their ends closed by a head or cap 11 and a base 12, which cap and base are held in place by bolts 13 and nuts 14.

The upper central portion of the cap 11 is 30 raised to form a valve chest 15 which has bored out therein certain passageways for air inlet and air outlet. The chest 15 is bored out horizontally and has inserted therein a bushing 16 provided with ports which match the inlet passageway 17, and the outlet passageways 18, 19, 20 and 21. These passageways run around the bushing 16, and the ports 35 may be simply holes drilled thru the bushing. The outlet passageways 20 and 21 also serve, as inlet passageways.

Inside of the bushing 16 is a tubular valve 22 which is shorter than the bushing 16 by a 40 distance which is equal to the distance between the centers of any two of the adjacent passageways 18 to 21. The valve 22 is movable lengthwise in the bushing 16 and has ports which match the ports in the bushing 45 when the valve is at either extreme of its movement. The valve, however, has one less circumferential row of ports than in the bushing. The valve 22 is held from rotary displacement in the bushing 16 by a pin 23 in the valve which slides in the slot 24 in the bushing. The interior of the valve 22 is 50 divided into compartments by transverse heads 25, 26 and 27 so that two rows of ports lie between heads 25 and 26, and two rows 55 between heads 26 and 27. In the bushing 16, at a point where it matches the inlet pas-

sageway 17, is a small hole 28 (Fig. 4), and opposite this hole is a small channel 29 which runs lengthwise of the valve 22, as shown in Fig. 6. The ends of the channel 60 29 are reduced, as shown at 30, so that the ultimate opening is about the size of a pin hole. The open ends of the valve chest 15 are closed by plugs 31 which also serve as stops for the longitudinal movements of the 65 valve 22.

Screwed into the inner face of the head or cap 11 opposite the ends of the bushing 16 are plugs 32 which are bored out to receive the ends of the small pipes 33 and to permit 70 said pipes to reciprocate therein. The openings into which the plugs 32 are screwed are in communication with the interior of the bushing 16 thru the slot 24 at one end and a similar slot 34 at the other end. The upper 75 ends of the plugs 32 are reduced in diameter. Small holes 35, located as shown in Fig. 3, furnish communication between the exterior and interior of plugs 32.

On the pipes 33 are collars 36 so located 80 that when a collar is against its plug, the upper end of the pipe 33 will act as a valve to close ports 35. On each plug 32 is a cap 37 for limiting the downward movement of the pipe 33 so that it will just open the ports 85 35 and thus permit communication between the interior of the bushing 16 and the interior of the pipe 33. The lower ends of the pipes 33 extend thru the base 12 as shown in Fig. 5. 90

The base 12 is, in plan, the same shape as the cap 11, and has ports which serve as inlet openings for water. These ports are normally closed by inwardly opening flap valves 39 supported on bridges 40 and held 95 in place by bars 41. The pipes 33 run thru and are guided by the bridges 40. Secured on each pipe 33, as near as practicable to the bottom of the cylinder 10, is a water cup 42. This cup is counterbalanced by a weight 43 pivoted at 44 to a lug on the bar 41. The counterbalancing weight is so related to the weight of the cup 42 and pipe 33 that when the cup is submerged the weight 43 will raise the cup and consequently the pipe 33 to close the ports 35, while when the cup is out of the water and full of water, the weight 43 will be overbalanced and the pipe 33 will fall to open the ports 35. The cup 42 may in fact be 100 a float, and the weight 43 be dispensed with, but the construction shown avoids the diffi- 105 110

culty arising from leakage of the float. For the sake of simplicity of language, I will hereinafter refer to this device as a "float" when I wish to designate the action performed, and as a "cup" when I wish to refer to the specific construction by which I overcome one of the objections to an ordinary float.

On the bottom of the base 12 is a supplementary ring 51, and between this ring and the base is held a screen 52.

At the side of the valve chest 15, and forming a part of the cap 11, is a boss 45. This boss is cored out in the interior (see 15 Fig. 4) and has three openings to the outside of the cap 11. One of these is to the top of the cap 11 and is for the reception of the water discharge pipe 47, while the others are to the bottom of the cap 11 20 in the two cylinders 10 and are for the inner discharge pipes 48. The pipes 48 extend close to the bottom of the cylinders 10 and are provided with upwardly opening check valves, not shown. Secured in another boss 25 49, on the chest 15, is an air inlet pipe 50 which communicates with the passageway 17.

The pipe 50 is connected to a source of compressed air, preferably from a reservoir, and pressure is always on in passageway 17 30 which is in communication with this pipe. The pipe 47 leads to the place at which water is to be delivered and its discharge end is normally closed by a faucet. Flow of air thru the pipe 50 is prevented when 35 the faucet is closed because there is no place to which the air can force the water in cylinders 10.

Assuming that the parts are in the position shown in Fig. 3, that both cylinders 40 10 are full of water, and that the faucet at the discharge end of the pipe 47 is opened, then air will flow from passageway 17 thru ports in the bushing 16 and valve 22, and passageway 20 into the right hand 45 cylinder 10 and force the water therein up the pipe 48, thru the channel 46 and pipe 47 to the place of discharge. When the water falls below the float 42 this float and the pipe 33 will fall to open the ports 35 50 which communicate with the space at the right hand of the valve 22. As the spaces at both ends of the valve 22 are in communication with the full air pressure in pipe 50 thru hole 28, channel 29 and the 55 small openings 30, there is normally full air pressure at both ends of the valve 22. The ports 35 and the interiors of the pipes 33 are of much larger area than the openings 30, with a consequence that when the pipe 33 60 falls to open the ports 35, the compressed air in the space at the right of the valve 22 escapes thru the pipes 33 into the water in the base 12. There is no difficulty about this because the "head" of water in the base 65 is only that of which the pump is sub-

merged, while the pressure in the pipe 50 is sufficient to raise the water to a much higher level. The escape of this air leaves the air pressure at the two ends of the valve 22 unbalanced with the result that the high 70 pressure at the left end forces the valve to its extreme position to the right against the corresponding plug 31.

The shifting of the valve to the right connects the passageway 17 with 21 and permits the air pressure to enter the left hand cylinder 10 and force the water therein thru its pipes 48, the channel 46 and the discharge pipe 47. The same movement of the valve also connects the passageway 20 80 with the exhaust opening 18 and permits the compressed air in the right hand cylinder to escape. When this occurs, the valves 39 rise and water flows into the cylinder thru the ports 38 in the base. When the 85 water rises in the right hand cylinder above the float 42, the ports 35 will be closed and full air pressure will again accumulate at the right end of valve 22. This, however, will not affect the valve because full air pressure also exists at the left end until the float 90 in the left hand cylinder opens the ports 35 at that end. The various inlet and outlet passageways are so proportioned to each other that the cylinders will fill thru ports 95 38 more rapidly than they will empty thru pipe 47. When the water level in the left hand cylinder falls below its float 42, air will escape from the left end of valve 22 and permit the compressed air at the 100 right end to return the valve to its previous position.

It will be observed from the foregoing description that the opening and closing of air ports is controlled entirely by the pressure 105 of the air used to operate the pump, and that the opening and closing is controlled by the water level in the pump. Also, that the air valve is simple in construction, is a balanced 110 valve, and cannot become displaced or out of order. And further, that there are no floats to leak and no levers to get out of order.

The only lever of any kind is the loosely pivoted weight 43 confined within limited 115 space. The floats have a very short movement and have no work to perform other than to release the power. As a consequence they may be of relatively small size. The supplementary valves which open the exhaust for operating the main valve, being located below the main valve and discharging downward, serve to drain from the spaces at the ends of the main valve any 120 water that may accumulate therein.

What I claim is:—

1. In a pneumatic pump, two pump cylinders, a cap covering said cylinders and provided with an interior valve chamber, a 130 valve in said chamber, openings thru said

cap from the interiors of said cylinders to the ends of the valve cylinder, and supplementary valves located in said openings and each controlled separately by the water level of the cylinder with which it is associated.

2. In a pneumatic pump, a hollow valve provided with ports furnishing independent passageways therethru, a conduit by which air pressure is conveyed to the ends of the valve, two chambers to which air is admitted and from which it is exhausted thru the passageways in the valves, and means located in the chambers for controlling the pressure at the ends of the valve.

3. In a pneumatic pump, a main valve controlling the operation of the pump, means for applying compressed air to move the valve, a supplementary valve controlling

the application of air to the main valve, a float, a connection from the float to the supplementary valve for operating it, and means by which the air exhausted by a movement of the supplementary valve will be discharged thru said connection.

4. In a pneumatic pump, an air actuated valve for controlling the pump, a float and connections for opening an exhaust for the air used to actuate the valve, and means for discharging such exhaust thru said connections.

Signed at Chicago, Illinois, this 29th day of March, 1913.
